GEORGE MARVELL, OF ANNAPOLIS, MARYLAND

BAND FASTENER

Application filed August 29, 1930. Serial No. 478,742.

This invention relates generally to the class of band fastening devices and, while not necessarily restricted to such use, is particularly designed for detachably connecting together 5 the ends of the leg bands of linen knickers or other equivalent garment bands, without resorting to the commonly used types of metal buckles, clasps or the like.

It has been observed that linen or other 10 washable knickers have been provided with various forms of devices for fastening together the leg band ends, such as metal buckles, clasps or the like, which are ordinarily detached from the band when the garment 15 is to be laundered. Obviously, this is open to numerous objections and disadvantages, which it is the aim of the present invention to overcome by providing a simple, inexpensive but effectual means for fastening 20 together the band ends constituting a permanent part of the band and preferably constructed from the same material as the garment.

With the above recited and other objects 25 in view, reference is had to the following description and accompanying drawings, in which there is exhibited one example or embodiment of the invention, while the claims define the actual scope of the same.

30 In the drawings:

Figure 1 is a perspective view illustrating a band fastening means constructed in accordance with the invention, in its active position.

35 Figure 2 is a fragmentary enlarged view illustrating the band ends in unfastened relation.

Figure 3 is a similar view illustrating in full and dotted lines the initial steps incident to the fastening of the band ends.

40 Figure 4 is a similar view illustrating the fastened relation of the band.

Figure 5 is a sectional view therethrough taken approximately on the line 5—5 of Figure 4.

45 Referring to the drawings by characters of reference, A designates generally the leg encircling band of the garment B, the ends 6 and 7 of which are designed to be fastened together in embracing relation to the leg of the wearer. As is usual, the end 6 is provided

with an extending portion or tongue 8 of reduced width which is designed to be fastened or interconnected with a suitable fastening device carried by or formed on the opposite band end 7. In the present instance, the device with which the tongue 8 is associated for adjustably and detachably connecting the band ends is in the nature of a substantially triangular shaped pieces of material 9 which is preferably the same as that from which the 55 garment B and its band A are constructed and of sufficient thickness to lend the desired rigidity thereto, and said piece of material is secured at its corners 10, 11 and 12 to the band end 7, as clearly illustrated in the drawings. This construction and arrangement 60 present between said secured corners, free edges 13, 14 and 15, the former edges representing the altitude and base of a triangle and the latter the hypotenuse, said latter edge 65 being disposed obliquely to the length of the band.

In use, the fastening of the band ends is accomplished by first inserting the tongue 8 70 between the band end 7 and the free edge 13, so that its extremity protrudes beyond the free edge 15 in the manner illustrated in full lines in Figure 3. After the band A has been adjusted snugly to the circumference of 75 the leg, in accordance with the desire of the wearer, the portion of the tongue 8 protruding beyond the free edge 15 is folded over in the manner illustrated in dotted lines in Figure 3 of the drawings, and the portion of 80 the tongue which depends below the free edge 14 or base of the triangle is then inserted between the free edge 14 and the band and tucked in between the portion of the tongue which underlies the piece 9, in the manner 85 illustrated in Figure 4 of the drawings, or if desired, said depending portion may be tucked under the band end 7. Either of these arrangements has been found to effectually fasten the band ends 6 and 7 together 90 against accidental displacement and, obviously, avoids the use of metallic buckles, clasps or other equivalent devices which must necessarily be removed when the garment is laundered.

95 While there has been illustrated and de- 100

scribed a preferred embodiment of the invention, it is to be clearly understood that no limitation is necessarily made to the precise structural details herein exhibited, but 5 that variations and modifications which properly fall within the scope of the appended claims may be resorted to when desired.

What is claimed is:

- 10 1. In a band, means at one end for receiving and fastening the other end thereto including an element carried by and secured at its corners only to the first mentioned band end and having opposite longitudinally converging free edges and under and over which 15 element the second mentioned end of the band is received for securing the same in relative position against unintentional displacement.
- 20 2. In a garment band, means at one end for receiving and fastening the other end there- to including a substantially triangular mem- ber secured at its corners to the first men- tioned band end and presenting between said secured corners, free edges disposed at an angle to each other for co-action with the 25 other band end.
- 30 3. A fastening means for garment bands consisting of a triangular piece of fabric secured at its corners to one of the band ends and presenting between said secured corners, free edges disposed at relative angles to each other for reception of and co-action with the other band end.
- 35 4. In a means for fastening the ends of garment bands, a substantially triangular shaped element carried by and attached at its corners to one end of the band to present unsecured edges disposed at a relative angle to each other for receiving and co-acting with the remaining end of the band to adjustably 40 and removably secure said band ends together.
- 45 5. As a new article of manufacture, a de- vice for securing the opposite ends of a garment band together comprising a substan- tially triangular piece of fabric secured at its corners to one band end and adapted to receive and co-act with the other band end to adjustably and removably fasten the same against accidental displacement.
- 50 6. In a band, means at one end for receiving and fastening the other end thereto including an element carried by and secured at its corners to the first mentioned band end and presenting a plurality of free edges, two of 55 which edges converge longitudinally of the band and under and over the edges of which element the second mentioned end of the band is received for securing the same in relative position against unintentional dis- 60 placement.

GEORGE MARVELL.
